UNITED STATES PATENT OFFICE.

HENRY W. METZING, OF NEW YORK, N. Y.

PNEUMATIC ENGINE.

SPECIFICATION forming part of Letters Patent No. 417,493, dated December 17, 1889.

Application filed September 12, 1889. Serial No. 323,710. (No model.)

To all whom it may concern:

Be it known that I, HENRY W. METZING, a citizen of the United States, residing at New York, in the county of New York and State of New York, have invented new and useful Improvements in Pneumatic Engines, of which the following is a specification.

This invention relates to a pneumatic engine suitable for various purposes, such as actuating dental and other tools; and the invention consists in the details of construction set forth in the following specification and claims, and illustrated in the accompanying drawings, in which—

15 Figure 1 is a plan view, partly in section, of a motor. Fig. 2 is a view similar to Fig. 1, with parts in a different position than Fig. 1. Fig. 3 is a longitudinal section of the motor along $x x$, Fig. 4. Fig. 4 is a section of the 20 motor along $y y$, Fig. 3. Fig. 5 is a detail view of the cylinder.

Similar letters indicate corresponding parts. In the drawings, the letter A indicates a casing which incloses the cylinder B and the 25 main-valve chamber C. The supply-channel D leads into the valve-chamber, and E is the exhaust-channel leading from the valve-chamber. The valve-chamber is provided with the main valve F, and from the valve-chamber 30 lead the ports $b b'$ to the opposite ends of the cylinder B. The valve F is shown in form of a disk having some portions cut away, Figs. 1 and 2, and said valve has two gudgeons $c c'$, one of which engages with a suitable cavity 35 in the valve-chamber, while the other engages with a cavity in the cap G. Said cap closes the valve-chamber and is retained in place by the casing or shell A.

The valve F receives motion from a pin e, 40 which extends through a slot f in the valve-chamber and engages with a cavity or depression g (shown in broken lines, Figs. 3 and 4) in the piston H. When said piston is at one end of its stroke, the valve F occupies the position shown in Fig. 1. If air under pressure is now introduced through the supply-channel D, this air passes into the cylinder through port b' , and the piston is driven forward or to the position shown in Fig. 2, the air in front 45 of the piston escaping through the exhaust-port E. As the piston approaches the end of

its forward stroke the valve is moved to the position shown in Fig. 2, the compressed air passes into the cylinder through the port b , and the piston is driven backward or from the 55 position shown in Fig. 2, while the air at the back of the piston is driven out through the exhaust-port E.

From the casing A extends a hollow shank I, forming the guide for the piston-rod. This 60 piston-rod is reciprocated by the piston and can be provided at its free end with any suitable tool—such as a tracer—for making punctures into a suitable surface, or with a dental plugger or other tool.

The outer face of the cylinder B is provided with channels J K. The piston H has channels $L' M'$, and cushioning-valve chambers L M, provided with cushioning-valves N, having springs which normally move said valves to the position to close the channels $L' M'$. 65 Stems O project from said valves beyond the piston. When the piston nears the end of a stroke, (for example, its forward stroke,) the channel L' is opened, Fig. 3, by the corresponding valve N being moved through its stem O, striking the cylinder-head. Compressed air then passes from channel J into channel L' , and through valve-chamber L into the space between the front of the piston and the cylinder, thus forming a cushion which 70 prevents the piston front from slamming against the cylinder. When the piston nears the end of its backward stroke, the channel M' is opened, so that air passing through the 75 channels K M' forms a cushion which prevents the back of the piston from slamming against the cylinder-head. The channels J K lead from the space between the shell A and cylinder B to their respective channels $I' M'$ 80 in the piston. The course of one channel (the channel K) is plainly shown in Fig. 4. At their inner mouths the channels J K have enlargements $J' K'$, so that communication is readily obtained between the channels J K 85 and channels $L' M'$.

What I claim as new, and desire to secure by Letters Patent, is—

1. The combination of a casing A, having a supply-channel D at one side and an exhaust-channel E at another side, a cylinder B, located within the casing between the supply 90

and exhaust channels and having a cavity *g*, a valve-chamber *C* beside the cylinder, having ports *b* *b'*, opening, respectively, into opposite ends of the cylinder, and the oscillating valve *F*, having an attached pin *e*, engaged with the cavity of the piston, substantially as described.

2. The combination, with the piston having channels *L' M'*, provided with cushioning valves *N*, having projecting stems *O* for alternately opening the valves as the cylinder nears the ends of its strokes, of a cylinder provided

with channels *J K*, communicating with said channels *L' M'*, said cylinder having the supply and exhaust channels, the ports, and main valve, and being inclosed by a suitable casting, substantially as described.

In testimony whereof I have hereunto set my hand in the presence of two subscribing witnesses.

HENRY W. METZING.
